APPARATUS FOR MAKING A JOINT IN A
FLAT METAL SLEEVE FOR OVERLAPPING
PORTIONS OF METAL STRAPPING

William Charles Gillman, Hanwell, London, England, assignor to Packers Supply Company Limited, New Malden, Surrey County, England, a company of Great Britain

Original application November 25, 1944, Serial No. 565,135. Divided and this application November 28, 1945, Serial No. 631,321. In Great Britain October 23, 1943

2 Claims. (Cl. 81—9.1)

1 This invention relates to an apparatus for use in making joints of binding straps tensioned around a box, case, package or the like, and of the kind consisting of a generally flat sleeve, which may be bent from a channel-section clip in such manner that the sleeve is interrupted along the longitudinal centre line of one face, and which embraces overlapping portions of the binding strap, these overlapping portions being locked in the sleeve by the application of dies with pressure at both faces of the sleeve to indent the superimposed layers formed by the sleeve and the overlapping portions in a manner preventing relative longitudinal movement.

An object of the invention is to provide an improved apparatus whereby a joint of neat-appearance is easily made having in each longitudinal margin of the joint at least two indentations spaced apart longitudinally in one of the generally flat faces of the sleeve and one indentation in the other generally flat face of the sleeve and disposed between said two indentations.

The improved jointing apparatus according to the invention comprises a body, a die fixedly mounted on said body, two sets of projections on the working face of said die adapted to form two sets of indentations on one face of the joint to be formed, a pair of levers pivotally mounted on the body, working die faces on each of said levers adapted, when the levers are rocked about their pivots to co-operate with the fixed die to clenche the joint, and projections on the working die face of each of said levers adapted to form indentations on the other face of the joint.

The invention is illustrated by way of example in the accompanying drawings in which:

Figs. 1 and 2 are views from opposite faces of one preferred form of joint for the overlapping ends of metal strapping adapted to be produced by the apparatus according to the invention.

Fig. 3 is a view in perspective showing a form of channel-section clip adapted to be applied over the overlapping ends of the strap and bent to form the generally flat sleeve.

Fig. 4 is a sectional view of the produced joint, on a larger scale and taken on the line 4—4 of Fig. 1.

Fig. 5 is a view in side elevation of the improved apparatus according to the invention, for forming such a joint between the overlapping ends of metal strapping, the apparatus shown including means for tensioning the strapping around a box, case, bale, package or the like as a preliminary to the joint forming operation.

2 Fig. 5a is a sectional view taken on the line 5a—5a of Fig. 5.

Fig. 6 is a view in sectional elevation of the joint forming means taken on the line 6—6 of Fig. 5.

Fig. 7 is a view of a part of the mechanism shown in Fig. 6 with the joint forming parts in different positions, and

10 Figs. 8 and 9 are views of the upper and lower die and indenting members, Fig. 9 being taken on the line 9—9 of Fig. 7.

In the joint according to Figs. 1 to 4, 1 and 2 represent the overlapping ends of metal strapping to be joined, a convenient and usual material being mild steel $\frac{1}{2}$ in. in width and 26 S. W. G. (0.018 in.) thickness. The sleeve 3 enveloping the overlapping ends 1 and 2 may be about $\frac{3}{8}$ in. long, being formed in the case illustrated by the application of a channel-section clip of the form shown in Fig. 3, of mild steel and the same gauge as the strapping, to the overlapping ends 1 and 2 and bending the side walls 4, 5, to form a tube interrupted along the longitudinal centre line of one face as shown at 6 in Fig. 2. The sleeve may however be of uninterrupted tubular form and the strapping threaded through it as a preliminary to tensioning and jointing.

30 In the face of the sleeve 3 which forms the base of the clip, and along each border thereof are formed a set of three indentations 7, 8 and 9 (Fig. 2) the two sets being symmetrical with respect to the longitudinal centre line of the joint. As an example, the middle indentation 8 of each set is about $\frac{1}{16}$ in. long and spaced about $\frac{1}{8}$ in. from the end indentations 7 and 9 of the same set which are about $\frac{1}{16}$ in. long.

35 In the other face 4, 5 of the sleeve 3 are formed two symmetrical sets each of two indentations 10, 11 and the two indentations 10, 11 of each set, which are about $\frac{1}{8}$ in. long, are directly opposite the two intervals between the indentations 7, 8 and 9 on the same border of the first mentioned face.

40 45 All the indentations 7, 8, 9, 10 and 11 may be of the same uniform width throughout their length and tapering both in width, and length, from the surface level of the sleeve 3 to a blunt longitudinal ridge at their tips (Fig. 4).

It will be clearly seen from Fig. 4 that the superimposed layers composed of the upper and lower sides of the sleeve and the two enclosed strap ends 1 and 2 are thus jogged along the lines of the indentations 7, 8, 9, 10 and 11 into a substantially square topped wave form without

severing of the material and consequently with little or no reduction of the tensile strength thereof.

An example of an apparatus according to the invention for making such a joint is illustrated in Figs. 5-9 the embodiment as illustrated including means of known kind for tensioning the strap about a box, bale, case or the like.

The apparatus comprises a structure including a base 12 adapted to rest on the box, case or the like to be bound by the strapping, a spring biased pawl 13 mounted above the base and adapted to hold the end 1 of the strapping against the base 12 and to prevent longitudinal movement of the end 1 during the strap tensioning operation and a second spring biased pawl 14 mounted above the base and adapted to engage the overlapping end 2 of the strapping in such a manner that while permitting said overlapping end 2 to move in one longitudinal direction over the base 12 during the operation of tensioning the strapping around the box or the like, movement of said overlapping end 2 in the reverse direction is prevented by the gripping of said end 2 between the base 12 and the said second pawl 14.

The strap tensioning means comprises a block 15 pivoted for rocking movements at 15' on an upper part of the structure, and a hand lever 16 pivoted on the block 15 at 16' and having an arcuate extension 17 at one end adapted to co-operate with a lateral extension 18 on the block 15 to grip and move the end 2 of the strapping to tension it as the hand lever 16 is rocked in one direction i. e. in the clockwise direction into the position shown in Fig. 5. Movement of the hand lever in the reverse direction releases the grip of parts 17 and 18 on the strapping, these parts sliding relatively to the strapping to engage and grip the end 2 of the strapping at a new point when the hand lever 16 is again moved in the direction to tension it.

The means according to the invention for joining the ends 1 and 2 of the tensioned strapping with a joint of the kind illustrated in Figs. 1 to 4 is as follows:

A hollow metal body 19 (Figs. 5, 6 and 7) is mounted for up and down movements in guides provided on an inclined transversely disposed surface 20 on a pillar 21 (Fig. 5) upstanding from the rear portion of the base 12.

A lever 22 is pivoted at 23 on the body 19 and the arrangement is such that the body may be raised into the position shown in Fig. 5 against a stop 24 by rocking the lever 22 clockwise into the position shown, said lever engaging a part 25 of the pillar 21 forming a fulcrum. The body 19 moves downwards by gravity when the lever 22 is moved in the reverse direction.

In the lower end of the body 19 is provided a bridge piece 26 forming a support for a die 27 having a substantially flat working face provided with six projections 28 (Figs. 6 and 8) for forming the two sets of three indentations 7, 8, 9 in one side of the joint shown in Figs. 1, 2 and 4.

The two opposite longitudinal sides of the die 27 are recessed as shown at 29 (Fig. 8).

Two levers 30, 31 are pivotally mounted in the body 19 for rocking movements about parallel axes formed by two pins 32 disposed respectively on opposite sides of the die 27 and above the plane of its working surface.

The lower ends of levers 30, 31 in the lowered position of body 19 move in an aperture 12' provided in the base 12. Each lever 30, 31 is re-

cessed on its inner side near the lower end as shown at 33 and in the lower side of the recess 33 is formed a die 34 (Figs. 6, 7 and 9) having a substantially flat working face provided with two projections 35 for forming one or other of the two sets of two indentations 10, 11 of the joint shown in Figs. 1, 2 and 4.

The levers 30, 31 at their upper ends are pivotally connected through toggle links 36 with a plunger 37 guided for up and down movements in the body 19, perpendicular to the face of the die 27.

The plunger 37 is provided with rack teeth 38 meshing with a pinion 400 attached to the pivot spindle 23 which moves with the lever 22, so that levers 30, 31 are rocked about the pivots formed by pins 32 by continued movement of lever 22 in a counterclockwise direction in Fig. 5 after the body 19 has been lowered.

The teeth of the pinion are however interrupted so that driving engagement with the rack teeth 38 does not occur until the lever 22 has been rocked to move the body 19 into its lowered position.

On the inner face of each lever 30, 31 is mounted a fixed blade 39 of limited width, the end of which projects slightly below the level of the face of the die 27, when the levers 30, 31 are in the rest position shown in Fig. 6.

In operation, with the tool resting on the surface of the box or like body 40 (Fig. 5) to be bound, the metal strapping is arranged around the box, with the overlapping ends 1 and 2 over the base plate 12, and tensioned by rocking lever 16 to and fro as previously described. During these preliminary operations the hollow body 19 is in the raised position shown in Figs. 5 and 6, with the die 27 on the hollow body 19 spaced above the strapping and the dies 34 on levers 30, 31 outside the planes containing the longitudinal edges of the strapping.

Tensioning being completed, a channel section clip of the form shown in Fig. 3 is placed in position below body 19 with its base towards the face of die 27 and the channel walls 4, 5 disposed on opposite sides of the overlapping ends 1 and 2 of the strapping.

The hand lever 22 is now rocked counterclockwise in Fig. 5 to first permit the body 19 to move downwards and thereafter to lower the plunger 37 to move the toggle links 36 and the levers 30, 31 to make the joint.

As the levers 30, 31 are rocked from the position of Fig. 6 to that of Fig. 7, the dies 34 thereon engage the sides 4, 5 of the clip 3. The base of 55 the clip is urged against the die 27 and the sides 4, 5 bent up against the underside of the overlapping portion 1 of the strapping.

In the meantime however the ends of the blades 39 on the levers 30, 31 have moved into a position 60 where they project into the recesses 29 at each side of die 27 (Fig. 7) and over the edges of the base of the clip 3.

As the toggle links 36 and levers 30, 31 attain the position of maximum mechanical advantage, 65 the faces of the dies 34 come substantially parallel with the face of the die 27 on the hollow body 19 (Fig. 7) at such a distance therefrom that the clip 3 is securely clenched into the required sleeve form around the overlapping ends 1 and 2 of the strapping and the projections 28 and 35 on the cooperating dies 27 and 34 form the indentations 7, 8, 9, 10 and 11 of the joint.

A swinging movement of the lever 22 returns the levers 30, 31 to the open position and during 75 this movement the ends of the blades 39 on the

levers 30, 31 engage the edges of the now flattened clip or sleeve 3 from above and disengage the joint from the die 21.

The pawls 13 and 14 are disengaged from the strap in the usual manner and the tool moved to slide the base 12 from beneath the tensioned and jointed strap.

In the construction illustrated the lever 22 is provided with a long slot 41, into which lever 16 may enter as the lever 22 is moved in the counter-clockwise direction to make the joint.

I claim:

1. Apparatus for making a joint with a flat metal sleeve for overlapping portions of metal strapping, comprising a body, a die fixedly mounted on said body, two sets of projections on the working face of said die and extending in a direction away from said face, said projections being adapted to form two sets of indentations on one face of the joint to be formed, a pair of levers pivotally mounted on the body, a working die face on each of said levers opposed to said first mentioned working die face, adapted, when the levers are rocked about their pivots, to co-operate with the fixed die to clench the joint, and projections on the working die face of each of said levers, said projections extending in a direction away from the die faces of said levers and towards the face of the fixed die and being adapted to form the indentations on the other face of the joint; two projections, one on each of the pivoted levers, said projections moving with the pivoted levers and extending, in the same general direction as the two sets of projections on the fixed die, towards the surface of the joint adjacent the fixed die when the levers are in the clenching position, and engaging said surface, near its edge, by moving through the plane of the working face of the fixed die and in a general direction away from said face during return movement of the levers after formation of the joint, to disengage the joint from the fixed die.

2. Apparatus for making a joint with a flat metal sleeve for overlapping portions of metal strapping comprising a body, a pair of levers

pivotally mounted on said body, means for rocking said levers, a first die fixedly mounted on said body, sets of projections on the working face of said die and extending in a direction away from said face, said projections being adapted to indent the superposed layers in the joint during the clenching operation, a second die movable with respect to the first die, said second die being constituted by a working die face on each of said levers and being adapted, when the levers are rocked in one direction about their pivots, to co-operate with the fixed die to clench the joint, and further projections, one on each of the pivoted levers, said projections moving with the pivoted levers and extending in the same general direction as the projections on the fixed die, towards the surface of the joint adjacent the fixed die when the levers are in the clenching position and engaging said surface near its edges by moving through the plane of the working surface of the fixed die and in a general direction away from the said face on the fixed die during return movement of the levers after formation of the joint, to disengage the joint from the fixed die.

WILLIAM CHARLES GILLMAN.
